UNITED STATES PATENT OFFICE.

JAMES S. HAMBAUGH, OF JACKSONVILLE, ILLINOIS.

SUN-PRINTING FRAME.

SPECIFICATION forming part of Letters Patent No. 276,173, dated April 24, 1883.

Application filed February 17, 1883. (No model.)

To all whom it may concern:

Be it known that I, JAMES S. HAMBAUGH, of Jacksonville, in the county of Morgan and State of Illinois, have invented certain new and useful Improvements in Sun-Printing Frames, (Solargraphs;) and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view, showing the frame open for the insertion or removal of copy. Fig. 2 is a cross-section through one side of the frame closed, showing the copy - sheet and printing-sheet both in position; and Fig. 3 is a plan or face view of the transparent printing-sheet.

Similar letters of reference indicate corresponding parts in all the figures.

My invention has relation to sun - printing, and is specially adapted to the production of manifold copies, by the so-called "blue" process, of written matter of any kind. To this end it consists in the improved construction of a printing-frame or solargraph for exposing the printing-sheet and underlying copying-sheet to the action of the sunlight, substantially as hereinafter more fully described and claimed.

In the accompanying drawings, the letter A denotes a frame, made of wood or other suitable material, and preferably of square or rectangular shape. Within this frame is secured a pane, B, of heavy French plate-glass, which must be without air - bubbles or flaws of any kind. Another frame, C, hinged to one side of frame A, has a raised panel, D, covered on its inner side facing the glass with several thicknesses of cotton-batting or similar material, E, the edges of which are clamped between the raised panel D and its frame C, as shown at e in Fig. 2. The layers of batting are in turn covered with a piece of soft felt or flannel, F, the edges of which are bound to the edges or shoulders of the panel by a piece of thin braid or tape G and small brads or tacks H. On the opposite end of the glass frame A, B is hinged a cover, I, of wood or other suitable material,

and the several parts A, B, C, D, and I may 50 be fastened together by means of suitably-arranged hooks J or other fastenings.

The sensitive copying or manifold sheets on which the written matter is to be reproduced are prepared by the well-known blue process, 55 which, as it forms no part of my invention, does not require description here. These sheets are cut to the proper size to fit the frame, and are used with a printing-sheet of oiled textile fabric, such as oiled silk or transparent oil-cloth. 60 This sheet is shown at K on the drawings, while the sensitized copying-sheet is indicated by the letter L. The matter to be reproduced is drawn or written upon the transparent and pliable sheet of textile material with india - ink, not 65 only on account of its blackness, but because changes or erasures in the written matter can readily be made when required by rubbing the printing - cloth with a sponge or damp cloth, which leaves the printing-cloth without a mark 70 and ready to be written on again as soon as dry.

I am well aware that it is not new to print from transparent negatives of glass or tracing-paper or tracing - cloth; but neither of these 75 materials would satisfactorily answer my purpose. Glass cannot be written on with india-ink, neither is it pliable, and writing in india-ink upon ordinary tracing - paper or tracing-cloth cannot be erased with a wet cloth or 80 sponge without injury to the paper or cloth, the surface of which is not damp-proof.

By the construction of my improved solargraph, as herein described, the copying-sheet and printing-sheet are pressed firmly together 85 between the padded raised panel D E F and glass pane B, so as to effectually exclude both air and light. This insures a clear, distinct, and every way perfect print; and after the print has been made the lid or cover I may be closed 90 and fastened to exclude light until the frame is needed for another print or impression. A handle, M, is fastened to the middle frame, A, for conveniently carrying the apparatus.

Having thus described my invention, I claim 95 and desire to secure by Letters Patent of the United States—

The improved frame or solargraph for solar

printing herein shown and described, composed of the middle frame, A, having glass pane B, hinged part C, having raised panel D, provided with the padding E, clamped between the panel 5 and frame, and covering F, and hinged lid or cover I, all constructed and combined substantially as and for the purpose herein shown and specified.

In testimony that I claim the foregoing as my own I have hereunto affixed my signature to in presence of two witnesses.

JAMES S. HAMBAUGH.
